Primary Examiner — Khawaja Anwar*Assistant Examiner* — Taylor O Mortorff(74) *Attorney, Agent, or Firm* — Justin Lampel(57) **CLAIM**

The ornamental design for a disposable dust collector bag, as shown and described.

DESCRIPTION

FIG. 1 is a perspective view of a disposable dust collector bag showing the claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of FIG. 1 thereof; and,

FIG. 10 is a scenario view thereof.

The dash-dot lines illustrate the boundary of the enlarged views and form no part of the claimed design.

1 Claim, 10 Drawing Sheets(56)
